SLOW WAVE STRUCTURE FOR USE IN A MAGNETRON

Se Puan Yu, Schenectady, N.Y., assignor to General Electric Company, a corporation of New York
Filed Oct. 5, 1960, Ser. No. 60,739
17 Claims. (Cl. 315—39.69)

This invention relates to slow wave structures and more particularly to a new and improved slow wave structure for use in a magnetron and adapted for preventing the magnetron from operating in a spurious mode or at an undesired frequency.

The conventional magnetron oscillator has an anode comprising a re-entrant series of coupled resonant cavities. Such a resonant slow wave structure has a number of fundamental resonant modes equal to one-half the number of resonant cavities plus one. Besides these fundamental modes, there are high-order bandpasses and each bandpass has spatial harmonics. Therefore, the conventional magnetron anode has an infinite number of resonant modes. When the magnetron is operated as a pulsed oscillator, a regenerative growth of high frequency energy is possible in many of the mode points through which the voltage sweeps during the rise and decay of the pulse. Further, any temporary lack of emission can cause the device to lock-in on a spurious mode having a synchronous phase velocity corresponding to the desired voltage during the pulse. This operation in spurious modes has previously placed an upper limit on the maximum power output and life of the pulsed magnetron oscillator.

It is, accordingly, an object of this invention to provide a magnetron which will assuredly operate at the predetermined mode and frequency for which it was designed to operate.

It is a further object of this invention to provide a slow wave structure which will support an electromagnetic wave of only a predetermined frequency.

It is a further object of this invention to provide a slow wave structure which presents a uniform impedance to an electromagnetic wave of a design mode and frequency and which presents a non-uniform impedance to other electromagnetic waves.

It is a further object of this invention to provide a magnetron in which all longitudinal modes of operation are eliminated.

Briefly stated, in accordance with one aspect of this invention, an anode block for a cavity resonator is provided in which the resonant cavities are of different sizes. Cooperating with the cavities are strapping rings including sections which are predeterminedly dimensioned such that the impedance presented by each cavity and the respective sections of the strapping rings associated therewith is uniform for the design mode and frequency but is not uniform for any other mode or frequency.

In copending Donald A. Wilbur application Serial No. 65,716, filed Oct. 28, 1960, entitled "Mixed Lines Crossed Fields Oscillator or Amplifier" and assigned to the assignee of the present application, there is disclosed and broadly claimed apparatus embodying a slow wave structure having two or more portions with frequency versus phase shift per section characteristics which intersect for only one frequency. The invention of the said Wilbur application was made prior to my invention and, therefore, I make no claim to the broad invention of the said Wilbur application and I claim herein only an improvement, of the broad invention, embodying strapping means having sections of different sizes.

2

For a better understanding of the invention, reference may be had to the accompanying drawings in which:

FIG. 1 shows a plan view of a magnetron anode block embodying certain aspects of the invention;

5 FIG. 2 shows developed views of the strapping rings to be used with the embodiment shown in FIG. 1;

FIGS. 3 and 4 show the strapping rings of FIG. 2 attached to the anode block of FIG. 1;

10 FIG. 5 shows a partially sectionalized view of an anode block utilizing the embodiment of the invention shown in FIG. 1;

FIG. 6 shows a plan view of a magnetron anode block including strapping rings using another embodiment of the invention; and,

15 FIG. 7 shows developed views of the strapping rings shown in FIG. 6.

In FIG. 1 is shown an anode block 1 employing one embodiment of the invention which may be used in any cavity resonator magnetron. The anode block 1 is adapted for encircling and cooperating with a concentric cathode 9 and includes ten segments or vanes 11 through 20 which form ten resonant cavities 21 through 30 in the block 1. Of course, the use of ten cavities is merely a matter of design choice, and any desired number of such cavities may be used.

As shown in FIG. 1, the cavities 21 through 30 are of three different sizes, with cavities 21 and 26 being of a first size, cavities 22, 24, 28 and 29 being of a second size and cavities 23, 25, 27 and 30 being of a third size.

30 As will be seen from the following, the number of different sizes which the cavities can take need not be limited to three, but may be any number greater than one, up to and including the total number of cavities used.

FIG. 2 shows developed views of strapping rings 2, 3, 4 and 5 to be used with the anode block 1 and FIGS. 3, 4 and 5 show the strapping rings 2, 3, 4 and 5 attached to the anode block 1. The strapping ring 2 is conductively attached, as by brazing, to segments 12, 14, 16, 18 and 20 at points 12', 14', 16', 18' and 20', respectively, of ring 2; and ring 3 is in a like manner connected to segments 11, 13, 15, 17 and 19 at points 11', 13', 15', 17' and 19', respectively. In a like manner, strapping rings 4 and 5 are conductively connected to the corresponding segments at their correspondingly numbered positions.

40 As shown in FIGS. 4 and 5, each of the segments 11 through 20 has a slot 6 on one side thereof and a slot 7 on the opposite side thereof. The electrical connections between the strapping rings 2 and 3 and the segments 11 through 20 are made in the slot 6 and the electrical connections between the strapping rings 4 and 5 and the segments 11 through 20 are made in the slot 7.

45 Each of the strapping rings 2, 3, 4 and 5 includes sections 21' through 30' which pass through and cooperate with cavities 21 through 30, respectively. The dimensions or cross sections of the sections 21' through 30' are varied so that each cavity and the sections of the strapping rings 2, 3, 4 and 5 cooperating therewith present a uniform impedance at the design mode and frequency.

50 To any other mode and frequency, each different-sized cavity and the sections of strapping rings 2, 3, 4 and 5 cooperating therewith will present a different impedance. Thus, the anode block 1 with the resonant cavities 21 through 30 and the strapping rings 2, 3, 4 and 5 forms a slow wave structure 8 which presents a uniform impedance to the design mode and frequency of operation of a magnetron employing such a slow wave structure. Also, since the slow wave structure 8 presents a uniform impedance to the design frequency, it will support an electromagnetic wave of this predetermined frequency.

70 The dimensions of the various sized cavities and the

sections of strapping rings cooperating therewith may be related according to the equation:

$$y_n + y_r + y_s = 0$$

where

y_n = the admittance of the interaction space of the magnetron

y_r = the admittance of the cavity

y_s = the admittance of the strapping ring

These admittances may be defined by the following equations:

$$y_n = \sum_P j \sqrt{\epsilon_0 / \mu_0} \frac{k}{\beta l} \left(\frac{\sin \alpha s}{\alpha s} \right)^2 \coth \beta d$$

$$y_r = j \sqrt{\epsilon_0 / \mu_0} \frac{1}{\theta a} \left[\frac{J_0(ka)N_1(kb) - J_1(kb)N(ka)}{J_1(ka)N_1(kb) - J_0(kb)N_1(ka)} \right]$$

$$y_s = j Y_0 \left[\frac{\cos 2kl - \cos \frac{4\pi n}{N}}{\cos \frac{2\pi n}{N} \sin kl - \cos kl \sin kl} \right]$$

where

$$P = n + mN$$

$$m = 0, \pm 1, \pm 2, \pm 3, \dots$$

$$N = \text{number of cavities}$$

$$n = 0, 1, 2, \dots, N/2$$

$$j = \sqrt{-1}$$

$$\sqrt{\epsilon_0 / \mu_0} = \text{admittance of free space}$$

$$k = \omega / c$$

$$\omega = \text{angular frequency at which the device is to be operated}$$

$$c = \text{velocity of light in free space}$$

$$\alpha = \frac{2\pi P}{NL}$$

$$\beta = \sqrt{\alpha^2 - k^2}$$

$$l = \frac{\pi(r_a + r_c)}{N}$$

$$s = a\theta$$

$$d = r_a - r_c$$

$$Y_0 = \text{equivalent characteristic admittance of each pair of conductive strapping members as a two wire transmission line}$$

$$l = \text{average length of strap per cavity}$$

$$r_a = \text{radius of the anode}$$

$$r_c = \text{radius of the cathode}$$

$$\theta = \text{angle at which walls of cavity would intersect}$$

$$a = \text{distance from point where walls of cavity would intersect to front of cavity}$$

$$b = \text{distance from point where walls of cavity would intersect to back of cavity.}$$

In a magnetron employing the invention as shown thus far, the following dimensions have been found to be satisfactory, for example, for an operating frequency of 2800 megacycles per second:

The depth D of cavities 21 and 26 may be 0.441 inch. The depth of cavities 22, 24, 28 and 29 may be 0.401 inch. The depth of cavities 23, 25, 27 and 30 may be 0.471 inch. The thickness T of each of the strapping rings 2, 3, 4 and 5 may be 0.040 inch. The inner radius R_1 of the inner strapping rings 3 and 4 may be 0.693 inch. The inner radius R_2 of the outer strapping rings 2 and 5 may be 0.803 inch.

With reference now to FIG. 2, the height of the different sections of strapping ring 2 may be as follows: dimension A, the height of the section associated with cavity 21 may be 0.073 inch; dimension B, the height of the section associated with cavity 22 may be 0.105 inch; dimension C, the height of the section associated with cavity 23 may be 0.032 inch; dimension S, the height of the strapping ring 2 at 16', which is attached to anode

block 1 between cavities 25 and 26, may be 0.160 inch. The dimensions of the remaining corresponding sections of the strapping ring 2 and also of strapping rings 3, 4 and 5 may be the same as those previously given dimensions A, B, C and S.

In the embodiment above-described, four conductive strapping rings are used, with a first pair of concentric strapping rings alternately contacting adjacent segments on one side of the anode block and a second pair of concentric conductive strapping rings alternately contacting adjacent segments on the opposite side of the anode block. If it is desired, only two strapping rings may be used. When only two strapping rings are used, they may be positioned either both on the same side of the anode block or, preferably, one on each side of the anode block. In both instances, the strappings rings will alternately contact adjacent ones of the segments which divide the anode block into a plurality of resonant cavities.

In the embodiment described, the resonant cavities have been equally spaced from each other and the different sized cavities have been randomly disposed around the anode block. According to the invention, the different-sized cavities may be disposed in any desired manner. If desired, the different-sized cavities may form an ordered pattern such as a symmetrical geometric pattern.

In FIG. 6 is shown an embodiment of the invention in which an anode block 1 has an even number of different-sized resonant cavities including a cavity 41 which is smaller than any of the other cavities and a cavity 42 positioned diametrically opposite cavity 41 and which is larger than any of the other cavities. The remaining cavities are disposed around the anode block 1 equally spaced from each other and becoming progressively larger from cavity 41 to cavity 42. Strapping rings 43 and 44 alternately connect the adjacent segments which separate the adjacent cavities. Strapping rings 45 and 46, shown in FIG. 7, alternately connect the adjacent segments on the other side of the anode block 1. Again, the dimensions of the sections of the strapping rings cooperating with each cavity are such that each cavity, together with its cooperating sections of strapping rings 43, 44, 45 and 46, presents a uniform impedance when the magnetron employing the invention operates at its design mode frequency.

FIG. 7 shows developed views of the strapping rings 43, 44, 45 and 46 suitable for use with the embodiment shown in FIG. 6. Of course, this embodiment could also use only two strapping rings, as previously described.

While only an anode block and cathode have been shown and described, it is understood that they are to be used in conjunction with other elements which would usually be employed in a magnetron; such, for example, as a suitable envelope, power input and output means, a cathode heater, and electrical connections to the heater.

While the above-described embodiments are illustrative of the application of the principles of this invention, it is understood that the invention is not limited thereto. Specifically, the invention is not limited to any particular type of resonator structure but is equally applicable to resonant circuits employing vanes, slots or bores. Additionally, the invention is not limited to the number of resonant cavities shown or to the particular geometric arrangement of the cavities shown. Numerous other embodiments may be devised by those skilled in the art without departing from the spirit and scope of the invention.

What I claim as new and desire to secure by Letters Patent of the United States is:

1. A slow wave structure comprising a plurality of resonant cavities, said cavities being of a plurality of different sizes and extending in a single plane, a plurality of segments, one each of said segments separating adjacent ones of said cavities, and strapping means connecting alternate ones of said segments, said strapping means being comprised of a plurality of different-sized sections, each one of said different-sized sections cooperating with one

of said different-sized cavities to provide a slow wave structure having a uniform impedance for a predetermined frequency and which will support electromagnetic waves of said predetermined frequency.

2. In a cavity resonator magnetron, an anode block having a plurality of different-sized resonant cavities extending in a common plane therein, a plurality of segments, one each of said segments separating adjacent ones of said cavities, and strapping means connecting alternate ones of said segments, said strapping means being comprised of an annulus having a plurality of different-sized sections, said different-sized sections each being predeterminedly dimensioned relative to an associated one of said different-sized resonant cavities and cooperating therewith to provide a slow wave structure having a uniform impedance for a predetermined mode and frequency of operation of the magnetron.

3. A slow wave structure comprising a plurality of resonant cavities, said cavities being of at least three different sizes, a plurality of segments, on each of said segments separating adjacent ones of said cavities, and strapping means connecting alternate ones of said segments, said strapping means having sections of differing cross-sectional dimensions to cooperate therewith to provide a slow wave structure having a uniform impedance for a predetermined frequency and which will support electromagnetic waves of said predetermined frequency.

4. In a cavity resonator magnetron, an anode block having a plurality of resonant cavities therein, said cavities being of at least three different sizes, a plurality of segments, one each of said segments separating adjacent ones of said cavities, and strapping means connecting alternate ones of said segments, said strapping means having sections of different dimensions to cooperate therewith to provide a slow wave structure having a uniform impedance for a predetermined mode and frequency of operation of the magnetron.

5. In a cavity resonator magnetron, an anode block having a plurality of resonant cavities in said block, said cavities being of at least three different sizes, a plurality of segments, one each of said segments separating adjacent ones of said cavities, and strapping means comprising at least two circular conductive members, said members alternately contacting adjacent ones of said segments, each of said members having a plurality of sections each cooperating with respective different individual ones of said cavities, said sections being of at least three different sizes whereby each one of said cavities and the sections of said members cooperating therewith present a substantially uniform impedance to an electromagnetic wave of a predetermined frequency.

6. In a cavity resonator magnetron, an anode block having a plurality of resonant cavities therein, said cavities being of at least three different sizes, a plurality of segments, one each of said segments separating adjacent ones of said cavities, said cavities of different sizes being randomly disposed in said block, and strapping means connecting alternate ones of said segments, said strapping means having different size sections dimensioned to operate therewith to provide a slow wave structure having a uniform impedance for a predetermined mode of operation of the magnetron.

7. In a cavity resonator magnetron, a circular anode block having a plurality of resonant cavities being equally spaced from each other in said block, said cavities being of at least three different sizes, a plurality of segments, one each of said segments separating adjacent ones of said cavities, said cavities of different sizes being randomly disposed in said block, and strapping means comprising at least two annular conductive members, said members alternately contacting adjacent ones of said segments, each of said members having a plurality of sections cooperating with respective different individual ones of said cavities, said sections being of at least three different sizes whereby each one of said cavities and the sections of said members cooperating therewith present a substantially uniform impedance to an electromagnetic wave of a predetermined frequency.

tions of said members cooperating therewith present a substantially uniform impedance to an electromagnetic wave of a predetermined frequency.

8. In a cavity resonator, a circular anode block having a plurality of resonant cavities being equally spaced from each other in said block, said cavities being of at least three different sizes, a plurality of segments each having a first end and a second end, one each of said segments separating adjacent ones of said cavities, said cavities of different sizes being randomly disposed in said block, and strapping means comprising two pairs of concentric conductive rings, the first pair of said rings alternately contacting the first ends of the adjacent ones of said segments, the second pair of said rings alternately contacting the second ends of the adjacent ones of said segments, each of said rings having a plurality of sections each cooperating with respective different individual ones of said cavities, said sections being of at least three different sizes whereby each one of said cavities and the sections of said rings cooperating therewith present a substantially uniform impedance to an electromagnetic wave of a predetermined frequency.

9. In a cavity resonator magnetron, an anode block having a plurality of resonant cavities therein, said cavities being of at least three different sizes, a plurality of segments, one each of said segments separating adjacent ones of said cavities, said cavities of different sizes being disposed in a symmetrical geometric pattern in said block, and strapping means connecting alternate ones of said segments, said strapping means having different size sections dimensioned to cooperate therewith to provide a slow wave structure having a uniform impedance for a predetermined mode of operation of the magnetron.

10. In a cavity resonator magnetron, a circular anode block having a plurality of resonant cavities being equally spaced from each other in said block, said cavities being of at least three different sizes, a plurality of segments, one each of said segments separating adjacent ones of said cavities, said cavities of different sizes being disposed in a symmetrical geometric pattern in said block, and strapping means comprising at least two annular conductive members, said members alternately contacting adjacent ones of said segments, each of said members having a plurality of sections each cooperating with respective different individual ones of said cavities, said sections being of at least three different sizes whereby each one of said cavities and the sections of said members cooperating therewith present a substantially uniform impedance to an electromagnetic wave of a predetermined frequency.

11. In a cavity resonator, a circular anode block having a plurality of resonant cavities being equally spaced from each other in said block, said cavities being of at least three different sizes, a plurality of segments each having a first end and a second end, one each of said segments separating adjacent ones of said cavities, said cavities of different sizes being disposed in a symmetrical geometric pattern in said block, and strapping means comprising two pairs of concentric conductive rings, the first pair of said rings alternately contacting the first ends of the adjacent ones of said segments, the second pair of said rings alternately contacting the second ends of the adjacent ones of said segments, each of said rings having a plurality of sections each cooperating with respective different individual ones of said cavities, said sections being of at least three different sizes whereby each one of said cavities and the sections of said rings cooperating therewith present a substantially uniform impedance to an electromagnetic wave of a predetermined frequency.

12. In a cavity resonator magnetron, a circular anode block having an even number of resonant cavities equally spaced from each other around said block, and an equal even number of segments, one each of said segments separating adjacent ones of said cavities, a first cavity being smaller than any one of the other of said cavities, a second cavity being larger than any one of the other of said

cavities, said second cavity being diametrically opposed to said first cavity, the remaining ones of said cavities becoming progressively larger from said first cavity to said second cavity, and strapping means connecting alternate ones of said segments, said strapping means being cross sectionally dimensioned to cooperate therewith to provide a slow wave structure having a uniform impedance for only a predetermined mode of operation of the magnetron.

13. In a cavity resonator magnetron, a circular anode block having an even number of resonant cavities equally spaced from each other around said block, an equal even number of segments, each one of said segments separating adjacent ones of said cavities, a first cavity being smaller than any one of the other of said cavities, a second cavity being larger than any one of the other of said cavities, said second cavity being diametrically opposed to said first cavity, the remaining ones of said cavities becoming progressively larger from said first cavity to said second cavity, and strapping means comprising at least two annular conductive members, said members alternately contacting adjacent ones of said segments, each of said members having a plurality of sections each cooperating with respective different individual ones of said cavities, said sections being of progressively different sizes whereby each one of said cavities and the sections of said members cooperating therewith present a substantially uniform impedance to an electromagnetic wave of a predetermined frequency.

14. In a cavity resonator magnetron, a circular anode block having an even number of resonant cavities equally spaced from each other around said block, an equal even number of segments each having a first end and a second end, one each of said segments separating adjacent ones of said cavities, a first cavity being smaller than any one of the other of said cavities, a second cavity being larger than any one of the other of said cavities, said second cavity being diametrically opposed to said first cavity, the remaining ones of said cavities becoming progressively larger from said first cavity to said second cavity, and strapping means comprising two pairs of concentric conductive rings, the first pair of said rings alternately contacting the first ends of the adjacent ones of said segments, the second pair of said rings alternately contacting the second ends of the adjacent ones of said segments, each of said rings having a plurality of sections each cooperating with respective different individual ones of said cavities, said sections being of progressively different sizes whereby each one of said cavities and the sections of said rings cooperating therewith present a substantially uniform impedance to an electromagnetic wave of a predetermined frequency.

15. A cavity resonator magnetron anode block as described in claim 11 in which the dimensions of said resonant cavities and said strapping rings are related according to the equation:

$$y_n + y_r + y_s = 0$$

where

y_n =the admittance of the interaction space of the magnetron

y_r =the admittance of the cavity

y_s =the admittance of the strapping ring

said admittances being defined by the following equations:

$$y_n = \sum_P j \sqrt{\epsilon_0/\mu_0} \frac{k}{\beta l} \left(\frac{\sin \alpha s}{\alpha s} \right)^2 \coth \beta d$$

$$y_r = j \sqrt{\epsilon_0/\mu_0} \frac{1}{\theta a} \left[\frac{J_0(ka)N_1(kb) - J_1(ka)N_0(kb)}{J_1(ka)N_1(kb) - J_0(ka)N_1(kb)} \right]$$

$$y_s = j Y_0 \left[\frac{\cos 2kl - \cos \frac{4\pi n}{N}}{\cos \frac{2\pi n}{N} \sin kl - \cos kl \sin kl} \right]$$

where

$$P=n+mN$$

$$m=0, \pm 1, \pm 2, \pm 3, \dots$$

N =number of cavities

$$n=0, 1, 2, \dots, N/2$$

$$j=\sqrt{-1}$$

$\sqrt{\epsilon_0/\mu_0}$ =admittance of free space

$$k=\omega/c$$

ω =angular frequency at which the device is to be operated

$$c=velocity of light in free space$$

$$\alpha = \frac{2\pi P}{NL}$$

$$15 \quad \beta = \sqrt{\alpha^2 - k^2}$$

$$L = \frac{\pi(r_a + r_c)}{N}$$

$$s=a\theta$$

$$20 \quad d=r_a - r_c$$

Y_0 =equivalent characteristic admittance of each pair of conductive strapping members as a two wire transmission line

$$l=average length of strap per cavity$$

$$25 \quad r_a=radius of the anode$$

$$r_c=radius of the cathode$$

θ =angle at which walls of cavity would intersect

a =distance from point where walls of cavity would intersect to front of cavity

$$30 \quad b=distance from point where walls of cavity would intersect to back of cavity$$

16. A cavity resonator magnetron anode block as described in claim 11 in which the dimensions of said resonant cavities and said strapping rings are related according

$$35 \quad to the equation:$$

$$y_n + y_r + y_s = 0$$

where

$$40 \quad y_n = the admittance of the interaction space of the magnetron$$

$$y_r = the admittance of the cavity$$

$$y_s = the admittance of the strapping ring$$

said admittances being defined by the following equations:

$$45 \quad y_n = \sum_P j \sqrt{\epsilon_0/\mu_0} \frac{k}{\beta l} \left(\frac{\sin \alpha s}{\alpha s} \right)^2 \coth \beta d$$

$$y_r = j \sqrt{\epsilon_0/\mu_0} \frac{1}{\theta a} \left[\frac{J_0(ka)N_1(kb) - J_1(ka)N_0(kb)}{J_1(ka)N_1(kb) - J_0(ka)N_1(kb)} \right]$$

$$50 \quad y_s = j Y_0 \left[\frac{\cos 2kl - \cos \frac{4\pi n}{N}}{\cos \frac{2\pi n}{N} \sin kl - \cos kl \sin kl} \right]$$

55 where

$$P=n+mN$$

$$m=0, \pm 1, \pm 2, \pm 3, \dots$$

N =number of cavities

$$60 \quad n=0, 1, 2, \dots, N/2$$

$$j=\sqrt{-1}$$

$\sqrt{\epsilon_0/\mu_0}$ =admittance of free space

$$k=\omega/c$$

ω =angular frequency at which the device is to be operated

$$65 \quad c=velocity of light in free space$$

$$\alpha = \frac{2\pi P}{NL}$$

$$70 \quad \beta = \sqrt{\alpha^2 - k^2}$$

$$L = \frac{\pi(r_a + r_c)}{N}$$

$$s=a\theta$$

$$75 \quad d=r_a - r_c$$

Y_0 =equivalent characteristic admittance of each pair of conductive strapping members as a two wire transmission line

l =average length of strap per cavity

r_a =radius of the anode

r_c =radius of the cathode

θ =angle at which walls of cavity would intersect

a =distance from point where walls of cavity would intersect to front of cavity

b =distance from point where walls of cavity would intersect to back of cavity

17. A cavity resonator magnetron anode block as described in claim 14 in which the dimensions of said resonant cavities and said strapping rings are related according to the equation:

$$y_n + y_r + y_s = 0$$

where

y_n =the admittance of the interaction space of the magnetron

y_r =the admittance of the cavity

y_s =the admittance of the strapping ring

said admittances being defined by the following equations:

$$y_n = \sum_P j \sqrt{\epsilon_0 / \mu_0} \frac{k}{\beta l} \left(\frac{\sin \alpha s}{\alpha s} \right)^2 \coth \beta d$$

$$y_r = j \sqrt{\epsilon_0 / \mu_0} \frac{1}{\theta a} \left[\frac{J_0(ka)N_1(kb) - J_1(kb)N_0(ka)}{J_1(ka)N_1(kb) - J_1(kb)N_1(ka)} \right]$$

$$y_s = j Y_0 \left(\frac{\cos 2kl - \cos \frac{4\pi n}{N}}{\cos \frac{2\pi n}{N} \sin kl - \cos kl \sin kl} \right)$$

where

$$P = n + mN$$

$$m = 0, \pm 1, \pm 2, \pm 3, \dots$$

N =number of cavities

$$5 \quad n = 0, 1, 2, \dots, N/2$$

$$j = \sqrt{-1}$$

$$\sqrt{\epsilon_0 / \mu_0} = \text{admittance of free space}$$

$$k = \omega / c$$

10 ω =angular frequency at which the device is to be operated

c =velocity of light in free space

$$\alpha = \frac{2\pi P}{NL}$$

$$15 \quad \beta = \sqrt{\alpha^2 - k^2}$$

$$l = \frac{\pi(r_a + r_c)}{N}$$

$$s = a\theta$$

$$20 \quad d = r_a - r_c$$

Y_0 =equivalent characteristic admittance of each pair of conductive strapping members as a two wire transmission line

l =average length of strap per cavity

$$25 \quad r_a = \text{radius of the anode}$$

$$r_c = \text{radius of the cathode}$$

θ =angle at which walls of cavity would intersect

a =distance front point where walls of cavity would intersect to front of cavity

30 b =distance from point where walls of cavity would intersect to back of cavity
